UNITED STATES PATENT OFFICE

THOMAS HENRY JONES, OF WOODTHORPE, AND ROBERT KIRKLAND MILLS, OF SHERWOOD, ENGLAND

KNITTED ARTICLE OR GARMENT

Application filed May 14, 1931, Serial No. 537,460, and in Great Britain May 9, 1930.

This invention comprises improvements in knitted articles or garments and in the production thereof, and has for its main object to provide a knitted article or garment which is shaped or fashioned and is immune or practically immune from laddering.

To this end the present invention resides broadly in the provision as a new article of manufacture of a shaped or fashioned knitted weft fabric composed wholly or in the main of ladder-proof or ladder-resisting fabric which embodies locked or tied stitches composed of and produced from the common ground or weft thread of the fabric.

By the term "knitted weft fabric" is meant that class of fabric which is produced by feeding ordinary ground or knitting thread weft-wise across the needles of a knitting machine in succession, said term being utilized to differentiate the fabric in accordance with this invention from that known as knitted warp fabric produced on a warp knitting machine.

In attempts previously made to produce a shaped knitted weft fabric having ladder-resisting qualities, it has been considered essential to employ a separate auxiliary locking thread for each needle in addition to the ordinary knitting or ground thread, said auxiliary thread being shogged from one needle to another to produce the non-ladder effect.

In accordance with this invention, however, the locked or tied stitches of the shaped fabric are, as before-stated, composed of the ground or weft thread employed in the production of the knitted web.

A class of knitted article which can readily be produced in accordance with this invention is a wrought full-fashioned stocking or sock which is wholly or in the main ladder-proof or substantially so, and by the expression "wrought" full-fashioned stocking is meant a stocking which is shaped during the knitting thereof, as differentiated from a stocking which is cut to the required shape subsequent to knitting.

The fabric is rendered ladder-proof or ladder-resisting by producing the non-roving

knitted loops or tied stitches in said fabric at regular or predetermined intervals.

For the purpose of more fully describing the nature of this invention reference will now be made to the accompanying drawings, wherein:—

Figure 1 illustrates a portion of suitable non-ladder selvedged fabric shaped or fashioned by narrowing and applicable for the production of a stocking or sock. 60

Figure 2 illustrates a portion of similar knitted fabric fashioned by widening.

Figure 3 illustrates successive steps in the needle operation required to produce fabric having tied or locked stitches on alternate knitted courses as shown in Figures 1 and 2. 65

Figure 4 shows in part-sectional elevation one side portion of a circular knitting machine suitable for knitting selvedged and fashioned stocking blanks of non-ladder fabric by continuous rotary motion. 70

Figure 5 shows in part-sectional elevation another portion of the machine illustrated in Figure 4.

Figure 6 is a diagrammatic illustration of the needle cams employed in the machine shown in Figures 4 and 5. 75

Figure 7 illustrates an adjustable needle-operating cam device adapted for use in a circular knitting machine for producing selvedged blanks of non-ladder fabric by reciprocation, the cam device being in this figure shown in a position for producing ordinary stitches. 80

Figure 8 is another view of the cam device shown in Figure 7 but illustrating same in a position for producing locked or tied stitches. 85

Figures 9 and 10 illustrate means for automatically adjusting the cam device shown in Figures 6 and 7 at predetermined intervals so as to change from unlocked to locked stitches and vice versa at will. 90

Figure 11 illustrates in part-sectional end elevation means for producing non-ladder fabric blanks on a flat bar knitting machine. 95

Figure 12 is a front elevational view of the dual needle-operating cams and displaceable cam truck shown in Figure 11.

Figure 13 illustrates in front elevation 100

means for rendering each needle cam operative on alternate knitted courses.

Figure 14 is an enlarged view of the upper part of Figure 11.

Figure 15 is a plan view of a slur cock and means for automatically adjusting same at each knitted course so as to vary the length of thread loops sunk on the needles.

Figure 16 is a detail view showing in part-
10 sectional front elevation the means for adjusting the slur cock.

Figure 17 shows a double latch needle with flexible hook and transfer point acting thereon, such as may be employed in a flat bar ma-
15 chine.

In one convenient method of producing the non-ladder fabric, tied or locked stitches are formed by tying or binding one needle loop upon another, this being advantageously ef-
20 fected by the employment of plural latch needles operating first to draw a loop of newly fed thread through a cleared loop and subsequently to pass said new loop closely around said cleared loop.

25 In Figures 1 and 2 selvedged non-ladder fashioned fabric is illustrated composed of alternate courses of locked and unlocked stitches, i. e. tied and tying stitches, and in the production of such fabric double latch
30 needles are employed and operated in the manner more clearly shown in Figure 3. In this figure the position indicated at A is that at which the needle has been raised to clear an old loop *a* below the top latch 1*a* and new
35 thread *b* is fed into the hook 1*c*, the needle being then lowered to cast off the old loop *a* over the new loop *b* which latter is retained in the hook, thus producing an ordinary knitted stitch. On the next upward motion of
40 the needle same is brought to the position C at which the loop *b* is cleared below the top latch 1*a*. A short downward motion is then imparted to the needle sufficient to cause the loop *b* to pass beneath the top latch 1*a* and at
45 the back of the bottom latch 1*b* as shown at position D. The needle then continues to rise to the position indicated at E which is higher than that indicated at A, and at this position the loop *b* has been cleared below
50 the lower latch 1*b* (which latch has been lowered by the engagement therewith of said loop *b*) and another thread *c* is fed between the two latches 1*a*, 1*b*, while the needle is maintained raised.

55 On the next succeeding downward movement of the needle the loop *b* appertaining to the previously formed ordinary stitch passes upwardly along the needle, closes the lower latch 1*b* on to the upper latch 1*a*, and passes
60 into the hook above said top latch 1*a*, the newly fed thread loop *c* being retained between the two latches. During this part of the motion the loop *c* is drawn through the loop *b* as indicated at position F, and on the
65 continued downward motion of the needle the

loop *c* rises on the needle, lifts and closes the top latch 1*a* on to the hook 1*c* and is cast off said needle, thus becoming tied upon the loop *b* and constituting a locked stitch as indicated at position G. This cycle of operations is then repeated.

The shaped blanks of non-ladder fabric can be produced on either a circular or flat bar knitting machine.

For example a circular knitting machine may be employed such as that described in the specification of prior Patent No. 1,690,-729, which machine operates to produce flat fashioned or shaped fabric with selvedged edges by imparting continuous rotary motion to the needle-operating means. On such a machine, which is illustrated in Figures 4, 5 and 6, a plurality of independent selvedged blanks can be simultaneously produced by employment of two continuously and oppositely rotating needle cams 2 and 3 (see Figure 6) and by also employing two continuously and oppositely rotating sinker cams, said oppositely moving cams being arranged to pass one another at positions in the ma-
90 chine void of needles.

All of the needles in the machine are operated by each of the stitch cams, which cams operate alternately, independent thread feeding means being provided for each fabric blank being produced, and each of said feeds (one of which is shown at 4 in Figure 4) being traversed first in one direction and then in an opposite direction, as described in the aforementioned specification, so as to cause 100 successive courses to be knit in opposite directions.

In order to produce on this type of machine alternate courses of locked or tied stitches cams 2 and 3 are differently designed, 105 the cam 2 being of the customary formation applicable for producing ordinary or unlocked stitches, while the cam 3 is designed to raise the double latch needles 1 to a higher position than the cam 2 so as to cause the thread to be fed between the latches instead of into the needle hook and by so doing produce tied or locked stitches in the manner shown in Figure 3.

It will be appreciated that as the cams 2 115 and 3 operate on the needles in succession, alternate courses of locked or tied stitches are produced.

The width of the fabric, or each fabric portion being knitted, is varied during production, this being conveniently effected by simultaneously raising from an inoperative to an operative position a predetermined number of needles at predetermined intervals at each side of the group or groups of operative needles so as to widen the fabric to the required extent.

For this purpose a pair of lifting elements 5 may be provided (Figures 4 and 5) one of such elements being fixed to a circumferen-
130

- tially toothed ring 6 and the other to a second circumferentially toothed ring 7 accommodated within an annular recess in the first-named ring 6. These two lifter rings 6, 7 are 5 raised and lowered at predetermined intervals by means of a plurality of suitably spaced rollers 8 which are normally accommodated within recesses 9 in a relatively stationary ring or member 10 but are caused at 10 the required intervals to ride upwardly out of said recesses 9 and thereby lift the rings 6, 7 with the lifting elements 5.
- The movement of the rollers 8 may be effected from a projection 11 carried by and 15 rotating with the lower cam box 12, said projection 11 coacting with a radially slidable arm 13 linked to a lower radially extending arm 14, which arm 14 carries a bevelled nose portion 15 adapted when the arm 14 is moved 20 radially inwards to rotate the ring 16 on which the rollers 8 are mounted.
- The lifting rings 6, 7 are provided with circumferential ratchet teeth continually engaged by a pair of clawker arms 18 and 25 through the medium of these clawker arms 18 the lifter rings 6, 7 are rotated step by step in opposite directions to displace the lifting elements 5 to a position beneath successive needles for raising same.
- 30 The operation of the clawkers 18 for rotating the lifting rings may be effected intermittently from the aforesaid projecting elements 11 on the cam box 12 through the intermediary of mechanism similar to that 35 employed for displacing the aforesaid lifting rollers 8.

Another type of circular machine which may be employed is that wherein flat selvaged fabric is produced by reciprocation 40 of the needle-operating means, and in such a machine a needle-operating cam device is conveniently employed which can be adjusted at predetermined intervals to produce either locked or unlocked stitches.

45 One such adjustable cam device applicable to a circular reciprocating machine is illustrated in Figures 7 to 10 of the accompanying drawings. The centre cam 19 upon which the needles rise to clear their old 50 loops and take fresh thread, is provided with a vertically displaceable peak portion 20 which when in the lowered position (as shown in Figure 7) causes the needles to rise to a height sufficient to receive new thread 55 in the needle hooks and produce ordinary or unlocked stitches. When, however, the peak portion 20 is fully raised to the position shown in Figure 8, the needles are raised to a position in which thread is fed between the 60 two latches and locked or tied stitches are thus produced, it being understood that in the production of locked stitches the cam is travelling in the direction indicated by the arrow in Figure 8.

65 When producing the locked stitches the

needles are caused to traverse a small auxiliary cam 21 during their upward movement to take thread, the purpose of said auxiliary cam being, as before-stated, to ensure that the old thread loops on the needles take up a position between and at the rear of the needle latches so as to lower the bottom latch during the subsequent upward movement of the needles.

Adjusted simultaneously with the peak portion 20 of the cam 19 are two other cam elements 22, 23, which elements, when the peak portion 20 is in the lowered position, are moved downwards to the position indicated in Figure 7 so as to cause the needle butts to traverse the path indicated in broken lines in said figure, whereas when the peak portion 20 is fully raised to produce locked stitches the two adjustable cam elements 22, 23 are raised to cause the needle butts to traverse the small auxiliary cam along the path indicated in broken lines in Figure 8.

If now the peak portion 20 and other displaceable cam elements 22, 23 are adjusted on the termination of each knitted course, it will be appreciated that during the motion of the machine in one direction ordinary stitches are produced and during the opposite motion locked stitches are produced, and in this way a fabric is made having locked 95 stitches on alternate knitted courses. One method of automatically adjusting the cam device on each knitted course is illustrated in Figures 9 and 10. The displaceable peak portion 20 of the centre cam 19 together with the two movable cam elements 22, 23 may be mounted on a single vertically slidable block or frame 24, the cam elements 20, 22, and 23 being secured to said block by pins 25 coacting with vertical slots 26 in the fixed portions 100 of the cam device.

Travelling with the cam box within which the needle operating cam device is installed is a horizontally slidable member 27 having an upstanding cam rise 28, said member 27 being frictionally carried within suitable bearings 29 secured to the cam box. On the termination of the motion of the cam box in one direction the frictionally carried member 27 may coact with a relatively stationary stop or lug 30 and by so doing slidably displace the member 27 to a position wherein a roller or truck 31 associated with the vertically displaceable cam block 24 moves downwardly from off the cam rise 28 on the member 27 either by gravity or under the influence of springs 32, thus lowering the peak portion 20 and cam elements 22, 23 to a position for producing ordinary stitches. At the 115 termination of the movement of the cam box in an opposite direction the slidable member 27 is also displaced in an opposite direction by engagement with a stop member 33 and in so doing the cam rise 28 is moved beneath the roller 31 so as to raise the block 24 and 120 125 130

with same the cam elements 20, 22 and 23, the needle operating cams being then adjusted to produce locked or tied stitches.

If at any time it is required to continue 5 producing successive courses of ordinary or unlocked stitches for any predetermined length of time, this can readily be accomplished by displacing the stop member 33 to a position wherein same will not coact with 10 a sliding member 27. One suitable method of accomplishing this is by slidably mounting the stop 33 and causing same to be pressed upwardly to an operative position by a rotary cam member 34 or equivalent device, a spring 15 35 functioning to lower the stop 33 to an inoperative position when same is out of engagement with the cam rise on the member 34.

In manufacturing stockings in accordance 20 with this invention on a flat bar knitting machine the non-ladder fabric can be produced by employing two differently designed cams for imparting different degrees of motion to the needle bar and needles carried 25 thereby, one cam functioning to raise the needles to a position to feed thread into the hooks thereof and the other to raise said needles to a position wherein thread is fed between the needle latches; means being employed for bringing either of said cams into 30 operation as required.

Referring to Figures 11 and 12 of the accompanying drawings two cams 36, 37 are fitted close together side by side on the customary cam shaft 38, the needle bar 39 being vertically reciprocated from said cams 35 through the intermediary of a pivoted lever device 40 carrying a cam truck 41 which is maintained by spring or other means 42 in 40 engagement with the cams and is adapted to ride thereon.

One cam 37 is so designed that the part 37a of said cam with which the truck 41 engages during feeding of thread by the thread guide 4a for locked stitches is somewhat lower than the corresponding part 36a of the cam 36 with which said truck engages while thread is being fed for a course of ordinary stitches, and in this way the needles are moved to two different heights depending upon which of the cams 36, 37 is operating upon the truck 41.

To bring the cams 36, 37 into operation alternately, the truck 41 is slidably displaceable upon a short spindle 43 extending laterally of the cams and carried by the two arms 40a constituting the lower portion of the lever device 40. This slideable truck is displaced at predetermined intervals from the one cam to the other through the medium of a pivoted fork 44, and it will be appreciated that the moving of the truck 41 from one cam to the other must be effected during a period in the motion of the machine when the peripheral faces of the two cams in the proximity of the

truck are flush or level with each other. One such period occurs shortly after the thread feeding operation and while the needles are being lowered, therefore, it is advantageous that the means provided for moving the truck 70 should operate during this period.

One method of displacing the cam truck 41 is illustrated in Figure 13, wherein at each end of the cam shaft 38 is fitted a gear wheel 45 meshing with another gear wheel 46 fitted 75 on a lay shaft 47 which may or may not extend the full length of the machine. The wheels 46 are advantageously twice the size of the wheels 45 so that same are rotated at half the speed of the cam shaft 38 and cams 80 36 and 37, and on each of said wheels 46 is a cam rise 48 extending approximately half way round each wheel, said cam rise 48 being alternately engaged by trucks 49 on centrally pivoted levers 50 which levers are connected 85 at their upper extremities to a longitudinally extending rod 51 to which the before-mentioned forked lever 44 is fixed. This arrangement is such that when the cams 36, 37 have been rotated to a position at which the needles 90 are being lowered, that is to say, after the thread has been fed to said needles, a truck 49 appertaining to one of the levers 50 is caused to rise on to a cam rise 48 appertaining to one of the gear wheels 46 and simultaneously 95 truck 49 appertaining to the lever 50 at the opposite end of the machine moves off its cam rise 48 and the rod 51 is longitudinally displaced so as to pivot the forked lever 44 and move the cam truck 41 from the one cam to 100 the other.

In an alternative arrangement, instead of displacing the cam truck 41 from one cam to another, the cams 36, 37 may themselves be slidably displaced relatively to the cam truck 105 upon the shaft 38 at the required times; while in another alternative arrangement the cam shaft 38 with cams 36, 37 fixed thereon may itself be moved axially so as to bring either of the cams into operation at predetermined 110 intervals.

When a course of locked stitches is being produced it is advantageous that a somewhat greater length of thread be drawn or sunk by the customary sinkers 52 so as to ensure 115 the production of an even fabric, and in order to accomplish this, the customary slur cock 53 operating through pivoted jacks 54 to displace the sinkers 52 and draw the thread, is, on alternate motions of the machine, i. e. on 120 alternate knitted courses, moved forward to a slightly greater extent.

This may be effected by providing at each end of the traverse of each slur cock 53 an adjustable stop 55 carried by an arm or bracket 56 fixed adjustably or otherwise to a longitudinally extending rod or bar 57 (see Figures 14 to 16). When the slur cock 53, which is traversed in the customary manner, reaches one end of its movement one of the 125

stops 55 coacts with an upstanding lug 58a on a wheel 58 mounted on a rearwardly extending screw-threaded portion 59 of the slur cock and transmits a small rotary movement 5 to said wheel 58 so as slidably to displace the slur cock 53 forwardly or rearwardly in accordance with the direction or rotation of said wheel 58, it being appreciated that at the opposite end of the traverse of the slur cock 10 the second stop 55 functions to rotate the wheel 58 in an opposite direction and consequently displace the slur cock also in an opposite direction.

By this means the sinkers 52 operate on 15 alternate knitted courses to draw more thread than on the remaining alternate courses.

When fashioning by narrowing on a flat bar machine it is advantageous to employ needles having hooks of a spring or resilient nature somewhat similar to that of a bearded needle, the customary transfer points 60 being adapted to coact with and press said flexible hooks and maintain same pressed during the transfer of a loop from the needle to the 25 point, the action of the point on the flexible hook being clearly illustrated in Figure 17. Narrowing is illustrated at the positions marked N in Figure 1.

When fashioning on a flat bar machine by 30 widening, all that is necessary is to feed thread to one or more additional needles at either or both ends of selected courses so as to produce additional stitches thereon. In Figure 2 positions at which additional needles 35 are brought into operation are indicated at W.

It will be appreciated that wrought full-fashioned stockings can be produced as above described on circular machines without fashion marks appearing on the finished article, 40 but in making stockings according to this invention on flat bar machines the usual fashion marks may be produced.

We claim:—

1. As a new article of manufacture a shaped 45 knitted weft fabric such as a full-fashioned stocking or sock composed wholly or in the main of ladder-proof or ladder-resisting knitted fabric which embodies locked or tied stitches composed of and produced from the 50 common ground or weft thread of the fabric, such stitches consisting of thread loops extending through and also around other thread loops.

2. As a new article of manufacture a shaped 55 knitted weft fabric such as a full-fashioned stocking or sock composed wholly or in the main of ladder-proof or ladder-resisting fabric which comprises stitch loops locked or tied by other loops produced from the same 60 weft thread as that forming the first-named loops, the legs or side portions of the tying stitches extending through and being twisted about corresponding legs or side portions of other stitches.

65 3. As a new article of manufacture a shaped

knitted weft fabric such as a full-fashioned stocking or sock composed wholly or in the main of non-ladder fabric embodying at predetermined intervals locked or tied stitches each consisting of a thread loop extending through and also closely around another thread loop. 70

4. As a new article of manufacture a shaped knitted weft fabric, such as a wrought full-fashioned stocking or sock, composed wholly 75 or in the main of non-ladder fabric which embodies locked or tied knitted stitches each formed by extending a loop through and twisting the legs or side portions thereof around the corresponding legs or side portions 80 of an interengaging thread loop in the same stitch wale.
